UNITED STATES PATENT OFFICE.

PAUL D. WRIGHT, OF EDGEWOOD PARK, PENNSYLVANIA.

CAR-DUMPING APPARATUS.

Application filed March 16, 1923. Serial No. 625,590.

To all whom it may concern:

Be it known that I, PAUL D. WRIGHT, a citizen of the United States, and resident of Edgewood Park, Pittsburgh, in the county 5 of Allegheny and State of Pennsylvania, have invented certain new and useful Improvements in Car-Dumping Apparatus, of which the following is a specification.

This invention relates to car dumping apparatus and more particularly to apparatus for picking up a car bodily and turning it over into such position that the contents will be quickly dumped therefrom.

One of the objects of the invention is the 15 provision of means for preventing the spillage of the material being dumped under the apparatus, said means being adapted to collect the spilled material from one dumping operation and to discharge it during the 20 next dumping operation.

Another object is to provide a car dumping apparatus with a novel form of spill apron composed of the novel combination and design of parts hereinafter described 25 and illustrated in the accompanying drawings.

In the drawings, Figure 1 is a transverse sectional elevation through a car dumper embodying my invention.

30 Figure 2 is an enlarged detail sectional elevation through the apron plates at one of the bumpers.

Figure 3 is a similar view to the one side of the bumpers.

35 Figures 4 and 4^a are detailed longitudinal elevations of the apron plates.

Referring more particularly to the drawings, the numeral 2 designates the dumping cradle as a whole which is substantially 40 U-shaped and is pivotally mounted along the upper edge of its dumping side 3 on a pivot shaft 4.

The closed or bottom side of the cradle 2 is adapted to normally rest upon a foundation 45 5 and has tracks 6 mounted thereon to receive the car 7 to be dumped.

The cradle is provided with hook members 8 adapted to be engaged over the top of the car 7 to lock it in place on the cradle.

50 The dumping side of the cradle is provided with a side spill apron 9, which terminates an appreciable distance above bottom spill apron 10, and a bridging apron 11 is mounted so as to bridge the space between the aprons 9 and 10.

The side apron 9 is composed of a plu-

rality of plates rigidly secured to a framework 14 which is supported on arms or columns 15. The columns or arms 15 are pivotally supported at their lower ends on a 60 shaft or pivot bar 16 to permit the lateral movement of the apron 9. Suitable cylinders 17 are provided for moving the apron 9.

The cradle 2 and side apron 9 so far described are of well known construction with 65 the exception that the side apron is extended somewhat below the level of the side aprons heretofore used. In operation the cradle is adapted to be swung around the pivot shaft 4 to a substantially inverted position (as 70 shown in dotted lines in Figure 1) by means of cables and overhead operating mechanism to discharge the ore or other material from the car 7. During the dumping operation a certain amount of the ore or other material will fall or spill onto the apron 9 and when the car and cradle is returned to the starting position the spilled material will fall down between the car and apron and into the pit beneath the cradle. During the 75 continued operation of the device the spilled material will collect in the pit beneath the cradle to such an extent that it will interfere with the operation of the cradle and the dumping operations must be suspended 80 until the spilled material is removed.

In order to prevent the spilled material from collecting in the pit below the cradle I have provided the rigid bottom apron 10 which is rigidly secured to the track 85 stringers 19 and has the bridging apron 11, which is composed of a plurality of plate segments 20, hingedly mounted along its lower edge. The free or upper edge of the apron 11 overlaps and is slidably supported 90 on the side apron 9, thus providing for free transverse movement of the apron 9 relative to the bottom apron 10. A leather cover member 21, preferably formed from old belting, is secured to the aprons 10 and 11 so as 95 to overlie the hinged joint between said aprons and prevent the wedging of the spilled material in said joint.

The apron 9 is cut away at intervals to permit bumpers 23 to project therethrough. 100 The bumpers 23 are carried by upright arms 24 mounted on the pivot bar 16 and are adapted to be moved transversely by the cylinders 25. The bumpers 23 are adapted 105 to engage the side of the car and thus support the weight of the car while it is being inverted.

By the addition of spill aprons 10 and 11 all spillage into the pit below the cradle is prevented, since any material spilled is caught by the aprons 10 and 11 and held until the next dumping operation, when it will be discharged along with the material from the car being dumped.

I claim:

1. In a dumping apparatus a cradle 10 adapted to swing a loaded car into substantially inverted position, a side apron member mounted along the dumping side of said cradle and movable transversely toward and away from said car, a bottom apron secured 15 to said cradle, and a bridging apron hingedly secured to said bottom apron and having its upper edge loosely supported on and overlapping said side apron.
2. In a dumping apparatus a cradle 20 adapted to swing a loaded car into substantially inverted position, a side apron member mounted along the dumping side of said cradle and movable transversely toward and away from said car, a bottom apron rigidly secured on said cradle and a bridging apron having its bottom edge hingedly secured to said bottom apron and its upper edge loosely supported on and overlapping said side 25 apron.
3. In a dumping apparatus a cradle adapted to swing a loaded car into substan-

tially inverted position, a side apron member mounted along the dumping side of said cradle and movable transversely toward and away from said car, a bottom apron rigidly secured on said cradle and a bridging apron having its bottom edge hingedly secured to said bottom apron and its upper edge loosely supported on and overlapping said side 35 apron, said bridging apron being composed of a series of short lengths to facilitate its operation.

4. In a dumping apparatus a cradle adapted to swing a loaded car into substantially inverted position, a side apron member mounted along the dumping side of said cradle and movable transversely toward and away from said car, a bottom apron rigidly secured on said cradle, an inclined bridging apron having its bottom edge hingedly secured to said bottom apron and its upper edge loosely supported on and overlapping said side apron, and a flexible covering member secured to said bottom apron and said bridging apron and overlying the hinged connection between said aprons to prevent the unloaded material entering and wedging between said aprons.

In testimony whereof I have hereunto set my hand.

PAUL D. WRIGHT.
